UNITED STATES PATENT OFFICE.

ADAM DANNER, OF YONKERS, NEW YORK.

BARREL-WASHING MACHINE.

SPECIFICATION forming part of Letters Patent No. 637,854, dated November 28, 1899.

Application filed August 16, 1899. Serial No. 727,353. (No model.)

To all whom it may concern:

Be it known that I, ADAM DANNER, a citizen of the United States, and a resident of Yonkers, Westchester county, New York, have invented certain new and useful Improvements 5 in Barrel-Washing Machines, of which the following is a specification.

This invention relates to an improved machine for washing and scrubbing barrels.

10 The invention comprises novel means for lifting the barrels out of the soaking-tank, a novel construction and arrangement of the brushes, and various other features of improvement by which the manipulation is facilitated, a thorough cleansing is effected, and objectionable wear avoided.

15 In the accompanying drawings, Figure 1 is a side elevation, partly in section, of my improved barrel-washing machine; Fig. 2, a plan showing the scrubber in section on line 22, Fig. 1; Fig. 2^a, a detail of cam f³; Fig. 3, a detail of the brake mechanism; Fig. 4, an end view, partly in section, of the scrubber; Fig. 5, a detail of the mechanism for vertically adjusting the side brushes; Fig. 6, a detail of the top-brush holder; Fig. 7, a plan of the side brush and holder; Fig. 8, a perspective view of one of the side brushes; Fig. 9, a longitudinal section of the slide l on line 30 99, Fig. 10; and Fig. 10, a section on line 1010, Fig. 9.

20 The letter a represents the soaking-tank of the barrel-washer, provided with inclined bottom rails a' and side rails a², which are laterally adjustable, so as to center barrels of different sizes. Across the rear end of tank a is hung a main shaft b, which receives intermittent rotating motion from pulley b' in manner hereinafter described. To the shaft b are attached a pair of parallel lifters c c, Fig. 2, which raise the partly-filled barrel out of tank a and transfer it to a pair of inclined rails d, along which it rolls to the scrubber. Each lifter c is made in the form of a 25 true circle, which turns on its center, and is provided with a segmental recess c', that joins the perimeter of the circle at an acute angle to form a hook c². The two ends of the 35 notch or recess c' thus merge into a curved 40 edge that extends concentrically around the

center line of the shaft b, which constitutes the axis of the lifter.

The shaft b is so rotated that when the recess c' is opposite the row of barrels in tank a it dwells for a considerable length of time 55 to permit the foremost barrel e to roll over the beak of the hook into the recess. The shaft then makes a complete turn to convey the entrapped barrel to the inclined rails d and again present the recess c' to the line of 60 barrels. Thus each barrel has ample time to roll into the recess, and an empty lift is prevented.

The curved periphery of the lifters serves as a stop to hold the row of barrels back as 65 the lifters rotate and detain the next barrel at such a radial distance from shaft b that it will lie directly in front of the recess when the latter again faces the barrels. A cock a³ permits the sediments to be drawn off tank a. 70

The driving-pulley b' transmits continuous rotating motion to a counter-shaft f by wheels b² b³ b⁴ f' and chain f², the transmission shown in the drawings causing one rotation of shaft f for eight revolutions of pulley b'. 75 The shaft f carries a cam f³, the groove of which is engaged by a pin f¹⁰, passing through the slotted end of lever f⁴, the other end of which when thrown inward is adapted to lock the pulley b' to shaft b by clutch f⁵. At 80 each eighth revolution of shaft f the cam will so oscillate lever f⁴ as to lock the pulley to shaft b for a complete revolution of the pulley and to then release the pulley from the shaft. In this way the shaft b will participate in each eighth rotation of shaft f, and thus the intermittent rotating motion of the lifters c, hereinabove referred to, is obtained. By sliding pin f¹⁰ out of engagement with cam f³ the intermittent rotary motion of shaft b 85 may be stopped. A tappet f⁶ on shaft f operates a brake-lever f⁷, carrying shoe f⁸. This shoe engages a brake and balance wheel b⁵, fast on shaft b, Fig. 3, while such shaft is to remain stationary and releases it while the 90 shaft is to rotate. Thus a prompt and accurately-timed action is assured.

The inclined rails d deliver the barrels one by one upon the conical heads g' of a pair of parallel shafts g, hung across frame B of the 100

scrubber. One of these shafts is shown to be rotated from shaft f by sprocket-wheels f^9 g^2 and chain g^3 , and it in turn transmits motion to the other shaft g by sprocket-wheels g^4 and chain g^5 .

As a barrel is rapidly rotated by the heads g , it is subjected to the action of an upper brush that cleans its sides and of two lateral brushes that clean its heads and chime. All of these brushes are so hung that when a barrel rolls upon its seat they will be momentarily displaced by such barrel and will then at once resume their operative position. This feature I consider of importance, as it prevents the brushes from becoming used up or damaged by violent impact, and thus their life is greatly prolonged.

The upper brush h is curved to correspond to the contour of the barrel-staves. Its head h' is clamped to a holder h^2 , which is by a stop-hinge h^3 pivoted to a vertically-adjustable rack h^4 . This rack is engaged by pinion h^5 , by which it is set, and is locked in position by pawl and ratchet h^6 . The holder h^2 carries the sprinkler h^7 and is provided with a lever h^8 , upon which is mounted the weight h^9 , Figs. 1 and 6. When a barrel rolls upon its support, the brush will be displaced or tilted in the line of barrel motion and will swing back into its proper position when the barrel has settled upon its seat.

The side brushes for scrubbing the heads and chimes are laterally displaceable and are made of the peculiar form illustrated in Fig. 8—that is, the twigs, bristles, ratan, or other material which forms the scrubbing-body of the brush is short and straight along one edge of the brush-head i^2 , as at i , and is partly overlapped by the longer and inclined bristles i' , &c., that form the main body of the brush. The innermost tufts or rows of straight bristles i , which are overlapped by the inclined bristles i' , taper in length to form an inclined edge which is parallel to and abuts against the outermost inclined edge of the bristles i' . In this way open dirt-accumulating spaces between the bristles i i' are avoided and the tapering straight bristles serve as an abutment for the inclined bristles. The brush made as described will thus have a notched and undercut edge of peculiar construction which will engage the chime of the barrel, Fig. 7, while the inclined bristles i' will engage the head and also both sides of the recess beneath the chime. As this recess is very apt to harbor dirt, it is particularly desirable that it should be thoroughly scrubbed, and I consider the construction of the brush by which this desirable object is attained of great importance.

The brushes are capable of vertical and also of backward and forward adjustment to set them to barrels of different sizes, and they are furthermore adapted to slide laterally in and out, so as to clear the chime and engage

the head as the barrel rolls into its place. The construction is as follows: j are vertically-movable cross-heads engaging rails j' of frame B and connected to a crank-shaft j^3 by links j^2 . This shaft is locked in position by a pawl and ratchet j^4 and may be rocked to raise or lower the cross-heads by lever j^5 , engaging spanner-hole of head j^6 . Each cross-head j carries a bracket j^7 , to an upwardly-extending arm of which is fulcrumed an elbow-lever k , carrying weight k' . The lower arm of the elbow-lever engages a laterally-movable slide l , guided on bracket j^7 by rollers j^8 , engaging elongated slots l' of the slide. In order to set the brushes laterally farther in or out to fit shorter or longer barrels, the engagement between the parts k l is effected by an intermediate socket l^2 , which is adjustably clamped to slide l by screw l^3 . This socket is engaged by the lever k , and if the position of the slide is to be changed that of the socket is first correspondingly adjusted. The forward end of the slide l carries the bearings l^4 of a set-screw m , that engages a tapped lug n' of the brush-holder n . This set-screw permits the brush to be set in a radial direction to heads of different diameters, so that the brush may work well into the corners underneath the chime.

The operation of my improved machine will be readily understood. The brushes being properly adjusted, the barrels will be raised at intervals out of the soaking-tank and transferred by the lifters c to the scrubber. As each barrel rolls upon its seat it will swing the upper brush sidewise and slide the lateral brushes outward; but as soon as the barrel is properly seated the brushes will at once resume their operative positions by means of their weighted-lever connections. The barrel will now revolve rapidly several times, to be thoroughly rinsed and scrubbed, and will then be bodily thrown off its seat by impact with the next barrel as the latter rolls into place. Thus a continuous operation goes on and each barrel will be thoroughly cleansed in all its parts in an effective and reliable manner.

What I claim is—

1. A barrel-washer provided with a soaking-tank, a rotatable shaft, and a circular lifter concentrically mounted upon the shaft and having a curved segmental recess that merges into the perimeter of the disk which extends concentrically around the shaft, substantially as specified.

2. A barrel-washer provided with a frame, a brush adapted to engage the side of a barrel, a laterally-swinging brush-holder, a weighted lever secured to the brush-holder, a vertically-adjustable rack, and a stop-hinge for pivoting the brush-holder to the rack, substantially as specified.

3. A barrel-washer provided with a frame, a vertically-adjustable bracket, a slide, roll-

ers mounted on the slide which engage the bracket, a weighted lever pivoted to the bracket and actuating the slide, and a brush secured to the slide, substantially as specified.

5 4. A barrel-washer provided with a frame, a vertically-adjustable bracket, a slide, rollers mounted on the slide which engage the bracket, a socket, means for adjustably clamping the socket to the slide, a weighted lever pivoted to the bracket and engaging the socket, and a brush secured to the slide, substantially as specified.

5 5. A barrel-washer provided with a frame, a vertically-adjustable bracket, a slide, rollers mounted on the slide which engage the bracket, a weighted lever pivoted to the bracket and actuating the slide, bearings on the slide, a set-screw engaging the bearings, and a brush-holder engaged by the set-screw, substantially as specified.

15 6. A barrel-washer provided with a frame, a crank-shaft, means for rocking and locking said shaft, a pair of cross-heads, links that connect the crank-shaft with the cross-heads, brackets having arms and carried by the cross-heads, weighted levers pivoted to the bracket-arms, a pair of slides guided on the brackets

and actuated by the weighted levers, and brushes secured to the slides, substantially as specified.

7. A barrel-washer provided with a frame, a soaking-tank, a main shaft, a lifter mounted thereon, a loose pulley on the shaft, a counter-shaft driven thereby, a cam on the counter-shaft, and a clutch-lever and clutch adapted to intermittently lock the loose pulley to the main shaft, substantially as specified.

30 8. A barrel-washer provided with a frame, a soaking-tank, a main shaft, a lifter and brake-wheel mounted thereon, a loose pulley 40 on the main shaft, a counter-shaft driven thereby, a cam and tappet on the counter-shaft, a clutch-lever, clutch and brake operated thereby, the clutch and brake being adapted to intermittently engage the pulley 45 and brake-wheel respectively, substantially as specified.

Signed by me at New York city, county and State of New York, this 14th day of August, 1899.

AD. DANNER.
